PROJECTILE

Thomas A. Banning, Jr., Chicago, Ill.

Application October 16, 1943, Serial No. 506,508

4 Claims. (Cl. 102—51)

1

The present invention concerns itself with improvements in ordnance. The features herein disclosed are adapted for use in ordnance of various sizes and calibers; and also in ordnance of various types, such as cannon, howitzers, mortars, and the like.

The features of the present invention are also applicable to use with projectiles of either the solid shot type or the shell, shrapnel, or other types; and with either fixed or separate loading ammunition.

One principal feature of the present invention concerns itself with means and methods for recovering from the propellant charge a large portion of the energy of combustion and explosion which has heretofore been wasted, and transferring such recovered energy to the projectile in the form of greatly increased "muzzle energy" in the form of increased muzzle velocity; or conversely, making it possible to deliver to the projectile a desired or specified amount of muzzle energy or velocity with consumption of a greatly reduced propellant charge; or a combination of both of these results.

A further feature of the invention concerns itself with means and methods for delivering to the projectile the desired rotative energy in the form of revolutions per second at exit from the muzzle, with a shortened rifling (or no rifling), thereby making it possible to materially reduce the cost of the gun construction and also materially reducing wear and deterioration of the gun lining in service.

Since the acceleration of the projectile during its flight down the bore of the gun (in previous arrangements) has been due to the pressure of the gasses against the base of the projectile, it has heretofore been desirable to maintain said gas pressure relatively high up to the instant of exit of the projectile from the muzzle, in order to deliver the desired total muzzle energy to the projectile with a not too long barrel. The rate of combustion of the propellant has accordingly been adjusted to an amount which will maintain the desired pressure of the propellant gases.

Due to the relatively high gas pressure at termination of the projectile flight it has heretofore been the case that the energy remaining in the gases at the instant of exit of the projectile has been very high, constituting a very large proportion of the total energy of combustion of the propellant. Heretofore this energy has been completely wasted, and has appeared as noise of the explosion, and heat of the exiting gases, as well as other factors of waste to be hereinafter

2

considered. Conversely, the total muzzle energy of the projectile at instant of exit from the muzzle has been only a small proportion of the total energy of combustion; so that the "mechanical efficiency of the machine" has been very small.

A principal object of the present invention relates to means and methods whereby a large part of this heretofore wasted energy may be recovered in the form of additional muzzle energy of the projectile; or so that conversely, the amount of propellant needed to deliver a given total muzzle energy to the projectile may be materially reduced. In order that certain features of the invention may be better understood, 15 and their significance be better appreciated I shall next show generally the distribution of the energy of combustion of the propellant in a typical case, without use of the features of the present invention; and I shall then discuss those 20 portions of the energy which may be recovered by use of features of the present invention, and shall show how the distribution of the energy in the barrel during projectile flight may also be improved.

25 In a typical case of a three inch gun, the following assumptions are made; weight of projectile, 15#; weight of propellant, 4.874# of deca-nitrocellulose with 6% moisture and volatiles, and 4% stabilizer (giving 1,266,000 ft./lbs. per pound); travel of projectile to muzzle 139.89"; 30 weight of gun, 1950#; average friction of bands on gun bore, 5898# sq./in. on base of projectile; muzzle velocity (without my improvements), 2600 ft./secs.; rifling (without my improvements) 1/40 calibers; total volume of chamber plus barrel, 35 .78 cu. ft.; chamber capacity, 296 cu. in.; density of loading .4558.

With the foregoing, and without the improvements of my present invention the following general results are found;

40 Combustion is complete at about 41" projectile travel; maximum gas pressure, 36,000# sq./in.; maximum gas temperature, 3451 degrees above zero C.; total available energy of combustion, 2754.68 ft. tons; gas pressure at muzzle (instant 45 of exit of projectile), 13,750# sq./in.; temperature at muzzle (instant of exit of projectile), 2555.7 degrees above zero C.; adiabatic expansion commences after projectile travel of about 41"; total muzzle energy of projectile, 703.7 ft. tons. 50 Since the total energy of combustion of the propellant was shown to be 2754.68 ft. tons it is evident that there is a direct dead loss of 2050.98 ft. tons (2754.68—703.7); or, in other words, the 55 mechanical efficiency of the gun as a machine is

only 25.545% (being 703.7 divided by 2754.68). In this assumed case, also, the total muzzle energy of the projectile comprises 702.41 ft. tons translation energy and 1.29 ft. tons rotative energy, the R. P. M. at exit being approximately 15,600.

Manifestly, a large portion of this non-useful energy is in the form of heat and in other forms which may not be recovered; and in order to determine what portion thereof may be available for more efficient conversion to projectile energy I have made the following analysis:

The energy of the gases is expended in accelerating the projectile (both translation and rotative energy); in heating the parts with which the gas is in contact (principally the gun barrel), and this is a dead non-recoverable loss; in the form of friction of the projectile during its flight down the barrel, which energy also appears as heat, but is herein treated as a separate item of distribution, and which friction is chiefly due to engagement of the projectile bands with the lands of the rifling, and a portion of this energy item may be recovered if means be found to ensure the desired rapidity of rotation of the projectile with a shortening or elimination of the rifling; in the form of energy of recoil of the gun, carriage, etc., and this is a dead non-recoverable loss; and in the form of energy of velocity of the gases following the projectile down the barrel during its flight, and a portion of this energy is recoverable, as we shall presently see. Therefore, of the several items above listed we find that the energy of heating the barrel, etc. (not including friction loss), is a dead loss, the energy of recoil is a dead loss; but that the energy of friction may be partially saved, and the energy of gas velocity may also be partially saved.

Calculations in the assumed case show the following: Heat loss (non-recoverable), 216.95 ft. tons; friction loss (partially recoverable, possibly fully recoverable), 216.95 ft. tons; recoil loss (non-recoverable), 7.32 ft. tons; energy of velocity of gases following projectile down barrel (partially recoverable), 76.14 ft. tons. These several items, both recoverable or partially recoverable, and non-recoverable, add up to 517.36 ft. tons, of which 224.27 ft. tons are non-recoverable, and 293.09 ft. tons are at least partially recoverable.

If now, we subtract this amount of 517.36 ft. tons from the amount of 2050.98 ft. tons, previously found to be the total non-used energy, we find the difference to be 1533.62 ft. tons, and this item represents energy contained in the exiting gases at the instant of exit of the projectile from the muzzle, in addition to the energy of velocity of the gases following the projectile down the bore. If we add to this item of 1533.62 ft. tons, the amount of 76.14 ft. tons (velocity energy of the gases) we get the total amount of 1609.76 ft. tons, as representing energy all or a portion of which may be recoverable, and which amount is in addition to the muzzle energy of the projectile itself (according to previously known and used arrangements and methods) plus the dead, non-recoverable losses. In other words, my invention concerns itself with means and methods for recovering all or a portion of this amount of 1609.76 ft. tons, in the assumed case of a three inch gun and projectile, and transferring such recovered energy to the projectile in the form of added muzzle energy. Such amount of 1609.76 ft. tons comprises 58.437% of the total energy of the propellant powder,

so it is very evident that a substantial saving of this great loss is very much to be desired.

This energy of the exiting gases (1609.76 ft. tons in the assumed case), includes *a*, energy of compression of the fixed or perfect gases; *b*, energy of temperature of the gases at instant of exit; *c*, latent heat of evaporation of such vapors as H_2O , etc.; and *d*, the energy of velocity of the gases following the projectile down the bore. In the assumed case of the deca-nitrocellulose propellant, the terminal products comprise CO_2 , 2.73436#; CO , 1.24287#; H_2O , 0.15977#; H_2 , 0.11546#; and N_2 , 0.62154# (totaling to 4.874#); and these amounts of these several products will give the following free volumes at sea-level pressure and 32 degrees F., namely; CO_2 , 22.156 cu. ft; CO , 15.920 cu. ft; H_2O , 2.890 cu. ft; H_2 , 20.541 cu. ft.; and N_2 , 7.961 cu. ft. These products therefore will total 69.468 cu. ft. free volume at sea-level pressure and 32 degrees F. Yet it will be remembered that the total assumed volume of the chamber and barrel of the gun was only .780 cu. ft., so there has been a very large and almost instantaneous expansion of the products at the instant of exit of the projectile from the muzzle.

Now, as a matter of fact the gas temperature and pressure at the muzzle condition and just prior to exit and reduction of pressure, is, as previously shown, 2555.7 degrees C. (above zero, or 2828.7 degrees abs. and 13,750 lbs/sq. in.). If this gas be expanded to sea-level pressure from the temperature and pressure just above stated, under adiabatic conditions, and assuming $k=1.4$ (where

$$k = \frac{C_p}{C_v}$$

and when k for CO_2 equals 1.229; k for CO equals 1.405; k for H_2O equals 1.299; k for H_2 equals 1.404; and k for N_2 equals 1.407), then

$$\frac{k}{k-1}$$

equals 3.5; and we find that, for the assumed adiabatic expansion the terminal temperature at sea-level pressure will be 127.58 degrees C. above zero, or 261.6 degrees F. above zero. Using the formula $PV=RT$, we find that $R=3.7406$; and the volume at the terminal temperature and sea-level pressure is found to be 101.96 cu. ft. (the terminal temperature being, as just above shown, 261.6 degrees F. above zero), instead of 69.468 cu. ft. for the assumption of 32 degrees F., as heretofore stated.

Now the work to press back the surrounding atmosphere (at sea-level pressure), from the volume of .780 cu. ft. to the final volume of 101.96 cu. ft., is equal to 214,135 ft. lbs., or 95.69 ft. tons. Also, the temperature of these expanded gases is, as above stated, 261.6 degrees F., instead of 32 degrees F. (to which base the total energy of combustion of the propellant is referred); so we must determine the mechanical equivalent of the heat necessary to raise the gases of combustion from 32 to 261.6 degrees F. The weights of the gases have already been stated. The specific heats of these gases may be assumed as follows (same being at constant pressure); CO_2 , 0.187; CO , 0.245; H_2 , 3.410; N_2 , 0.243; and H_2O , 0.480. Upon making the determination we find that the energy thus accounted for is 114.54 ft. tons.

Now it was shown that the energy at the muzzle, all or a portion of which is recoverable, amounts to 1609.76 ft. tons. From this we must deduct

the amount of 95.69 ft. tons, representing the energy to expand the gases against the pressure of the atmosphere, and also must deduct the amount of 114.54 ft. tons, representing the non-available heat energy at completion of such expansion. These two deductions amount to 210.23 ft. tons, which, deducted from the amount of 1609.76 leaves 1399.53 ft. tons, or 50.805% of the total energy of combustion. In other words, we have a pool of slightly more than fifty percent of the total energy of combustion which is at present being wasted, but which is in the form of energy, some at least of which is recoverable to increase the muzzle energy of the projectile; or, conversely, by improvements presently to be disclosed herein, we may either increase the muzzle energy of the projectile for a given expenditure of propellant, or may secure the same muzzle energy as heretofore with expenditure of a less amount of propellant.

It is also here noted that under the assumed conditions the muzzle energy heretofore being secured amounts to only 25.545% of the total energy of combustion, and that the pool of additional energy, at least a portion of which is available by use of my present improvements, amount to 50.805% of the total energy of combustion; so that if we were able to translate all this heretofore wasted but available energy into additional muzzle energy we should be able to increase the muzzle energy to the amount of 76.350% of the total, (25.545 plus 50.805), or substantially three times as much as heretofore, making the gun three times as efficient as heretofore. Even if we could double the muzzle energy or the efficiency of the gun we should have a very substantial improvement. I shall presently show how the features of my present invention will serve to very greatly improve the operation and efficiency of the gun.

In the above analysis the item of friction of the projectile on the wall of the barrel during flight was shown to amount to 216.95 ft. tons, and this item was stated to be "partially recoverable, possibly fully recoverable." This item represents principally the friction of the bands on the lands of the rifling, and it has been an item which heretofore has been largely unavoidable due to the need of using rifling for producing all the rotary or spinning motion of the exiting projectile. I shall presently show, as one feature of my present invention, how the rotary motion of the projectile may be largely produced (if not entirely produced) by the reaction of the gases themselves; so that at least a portion of this wasted energy may be recovered and used. In the illustration which I shall presently enlarge herein of one application of the features of my present invention I have assumed a discontinuance of the rifling after a flight of about 84" down the barrel, at which time the projectile has been accelerated to 13,200 R. P. M., and the remaining rotative energy to bring the projectile up to 15,600 R. P. M., is supplied to the projectile by the reaction of the gases according to one feature of my present invention. By such shortening of the rifling I am able to greatly reduce the friction loss for a portion of the flight. The energy saving thus effected amounts to 73.869 ft. tons, which energy is directly available to increase the muzzle velocity of the projectile; so that with such shortened rifling the muzzle velocity is increased to 2735 ft./secs. instead of the 2600 originally assumed for the gun in question, and for which the present analysis is being

made. This is a direct increase of 10.497% as compared with the original muzzle energy of 703.7 ft. tons for the projectile.

The available energy, 1399.53 ft. tons, above referred to is released at the moment of exit of the projectile from the muzzle, and appears as disturbance, chiefly in the form of noise and shattering of the surrounding air into which the gases are discharged. At the instant just prior to this release of these gases they were contained within the barrel under a pressure of 13,750# sq./in., and at a temperature of 2555.7 degrees C. above zero (not abs.). Manifestly if these gases could be so handled as to be allowed to expand under conditions such that their energy could be converted into useful work transferred to the projectile, a very great improvement in the operation of the machine could be effected. Much of the energy of expansion of these gases as heretofore released (if not all such energy) is transferred into the form of gas velocity of some sort, but is not or has not been controlled usefully. I propose to make such control, and to thereby deliver a large part of this energy to the projectile before such projectile passes too far away from the gun muzzle.

I propose to so arrange the parts of the projectile, that the energy of expansion of these gases upon release may be effectively used for reaction against the base and/or other portions of the projectile, that a considerable portion of the energy may be converted into useful work of projectile velocity. If we consider the gun barrel as a nozzle which is suddenly opened upon the exiting of the projectile, the gases thus released will exert a certain pressure against the base portion of the projectile until said projectile has passed away so far that such action no longer is effective. This pressure will consist of two components; that of static pressure against the projectile base, and that of velocity or dynamic pressure due to the velocity at which the particles of gas are impinging against the projectile base. The former component will very rapidly fall to zero, due to the very rapid drop of gas pressure as soon as the muzzle of the gun has been opened by exit of the projectile; and likewise the latter or velocity component will also very rapidly fall to zero due to lateral expansion of the gases and complete lack of control of their movements in heretofore known and used arrangements. Consequently, in the past all this energy has been wasted, and it may be considered that effective work on the projectile has ceased as soon as said projectile has left the muzzle. In other words, heretofore substantially only the static pressure of the gases in the barrel has been effective to accelerate the projectile during its flight down the bore of the barrel, and the dynamic energy of the gases due to their velocities, especially at the moment of release has been completely lost as far as any effective projectile energy is concerned.

I propose to provide means and methods for recovering a large portion of this dynamic energy in the form of added projectile energy, delivered to the projectile during and adjacent to the exiting of the projectile from the muzzle. Such recovered energy is delivered to the projectile principally by reason of the reaction of the exiting gases during the interval of release of said gases from the high pressure which they still suffered at and during the interval of release, and is completely supplemental to the delivery of energy to the projectile by static pressure on the projectile's base.

It is well understood and known that a gas undergoing reduction of pressure, as in a jet or orifice exerts a reaction on the body from which it is being released; and also that in case of impingement of a jet of such gas against another body there is created a reaction on said body. Furthermore, a reaction is created in the case of a stream of gas undergoing violent change of direction, as in the case of a jet of gas impinging against a bucket so formed as to completely or largely reverse the direction of flow of the gas of such jet. In the case of a complete reversal of direction of the gas of a jet impinging against a properly formed or shaped bucket, or in the case of complete reversal of direction of flow of a stream of gas just prior to its exit from a jet, there will be produced a reaction substantially double the amount of the static pressure of the gas against the area against which it may be pressing, so that by the use of such reversal of direction we may secure very large reactions; and by properly arranging the parts we may direct such reactions effectively against the projectile itself, with consequent great benefits in the form of energy transferred to the projectile.

Sometimes I so form the base portion of the projectile itself that the gases exiting from the muzzle will react against the base of the projectile and have their direction reversed, thereby exerting a very large reaction against the base of the projectile, and adding a substantial proportion of energy to the projectile after the projectile has actually passed clear of the muzzle. In other cases I so form the projectile that the gases flow through a portion of the projectile (or an extension thereof) and then through the original exiting orifices, so that during the original portion of the gas releasing interval the gas release actually takes place through orifices constituting a portion of the projectile itself, or an extension thereof.

Since the reaction principle is used, it is possible to so arrange the parts that said reaction (due to dynamic conditions) will be either straight ahead against the projectile, or so that said reaction may also include a rotary component tending to promote the rotation of the projectile, either during its movement prior to complete exit from the muzzle or immediately thereafter. In either case such rotary force will add to the rate of projectile rotation, and thereby the work to be performed by the rifling of the barrel may be either completely eliminated (with complete elimination of the rifling) or partially eliminated (with corresponding reduction of the work to be performed by the rifling). In either case the muzzle velocity and muzzle energy of the projectile will be correspondingly increased (under the assumed pressures within the barrel) so that corresponding improvement and increase of efficiency of the operation will be secured.

The reformation or redesign of the base portion of the projectile to secure the desired reversals of gas direction may be effected substantially without material change of the overall dimensions of the projectile itself; and furthermore, it is possible to make these changes in projectiles of various shapes and sizes, including so-called "boat-tailed" projectiles and others. In some cases it may be desirable to increase the interval of time during which the reaction during release of gas pressure is being availed of, so as to greatly increase the energy recovery.

This may be accomplished by provision of gas passages in the tail portion of the projectile itself, through which passages the gases flow to the orifices for reaction release. Sometimes these passages may be provided as a permanent extension to the base portion of the projectile, with consequent increase of projectile length. In other cases I provide arrangements such that a portion of such extension (or all of it) may collapse forwardly over the body of the projectile after leaving the muzzle and during the early stages of free flight, thereby securing the benefits of my improvements without the disadvantages, if any, of the increase of projectile length.

15 In other cases I provide combined arrangements.

When such a collapsible arrangement as just referred to is used, the telescoping or collapsing portion of the projectile may move forward over the body of the projectile during free flight. Such movement will be secured by reason of the deceleration of the projectile with consequent tendency of such telescoping portion to slide forwardly over the body of the projectile, so that 20 after a relatively short interval of free flight the complete collapse will have occurred without the need of special provision therefor.

Other objects and uses of the invention will appear from a detailed description of the same, 25 which consists in the features of construction and combinations of parts hereinafter described and claimed.

In the drawings:

Figure 1 shows a longitudinal section through 30 the muzzle portion of a gun, and through a projectile exiting therefrom, said projectile being conveniently shown as of an armour piercing type, and provided with a base extension removably secured to the body of the shell, and 35 said base extension being provided with gas passages incorporating the reaction principles which constitute a portion of the present invention; and this base extension is also provided with a telescoping sleeve which will shut off the 40 orifices of these passages after the projectile has commenced its free flight, thereby preventing air flow through said passages at such time;

Figure 2 shows a section through the base portion of the projectile of Figure 1, free of the gun, 45 and with the sleeve in its advanced position where it shuts off the orifice of the passages;

Figure 3 shows a cross-section on the line 3—3 of Figure 2, looking in the direction of the arrows;

Figure 4 shows an outside or face view of the 50 rear and cylindrical portion of the projectile of Figures 1, 2 and 3, with the sleeve in forward or orifice closing position;

Figure 5 shows a view similar to that of Figure 1, but it shows a modified arrangement in which the passage extension of the projectile is itself 55 telescopingly carried by the body of the projectile, so that during the first portion of free flight said portion may slide forward over the body of the projectile, thereby reducing the overall length of the projectile to an amount not substantially larger than the length of the projectile without my improvements, and also serving to close the orifices of the passages;

Figure 6 shows an outside or face view of the projectile of Figure 5, with the extension portion slid forwardly during free flight, a small portion of the sleeve portion and base of the projectile being shown in section;

Figure 7 shows a cross-section on the line 7—7.

of Figure 5, looking in the direction of the arrows;

Figure 8 shows a view similar to those of Figures 1 and 5; but it shows still another modified form of projectile including a permanent extension portion on the base of the projectile, together with a collapsible sleeve in conjunction therewith, so that a very long passage arrangement is possible, with corresponding increase of the interval during which the reaction of the gases may be availed of;

Figure 9 shows a longitudinal section through the base and body portions of the projectile shown in Figure 8, removed from the muzzle of the gun, and with the sleeve portion slid forwardly or collapsed into the condition which it assumes during free flight;

Figure 10 shows a cross-section on the line 10—10 of Figure 8, looking in the direction of the arrows;

Figure 11 shows a cross-section on the line 11—11 of Figure 9, looking in the direction of the arrows;

Figure 12 shows a series of characteristic curves of performance of a typical three inch gun, to show the gas pressures, velocities, temperatures, energies, volumes, elapsed times, and other factors, to illustrate the energies which are available, and various factors of interest in an understanding of the features of the present invention; and

Figure 13 shows a cross-section through still another modified form of base portion of the projectile, and also shows by vector lines the directions and values of components of gas velocity of the exiting gases under a typical instantaneous set of conditions, and at a given instant in the flight of the projectile.

Figure 14 shows a cross-section on the line 14—14 of Figure 5, looking in the direction of the arrows; and

Figure 15 shows an end view of the projectile of Figures 5, 6 and 7.

I will first refer to Figure 12 showing certain characteristics of performance of a typical three-inch gun of well known type. The length of the gun is shown as abscissae along the line 101, and various factors of performance are shown by the ordinates along the line 101. The base of the projectile initially stands at the position 102, so that distances of travel are measured to the right from that position. For the gun and conditions assumed herein, the line of projectile velocity is shown at 103 (full line), and the line of gas pressure is shown at 104. The maximum pressure point is attained at 105 after a travel of substantially 25 inches down the bore. It is noted that the gas pressure commences to fall after the point 105 has been reached, indicating that thereafter combustion is taking place at a slower rate than the increase of volume behind the projectile's base. Still, combustion is not complete, and continues to substantially the point shown by the line 106. When the combustion is substantially complete (location of line 106) the adiabatic expansion commences and continues to the time of opening of muzzle by exit of the projectile therefrom.

The total energy (combustion of propellant) is shown by the line 107. It rises to the full combustion amount, and is then level from the point 70 forwardly to the muzzle, as shown by curve 107. The temperature of the gases within the chamber and bore is shown by the line 108. It remains substantially constant at the initial amount until combustion is complete, whereupon it falls due

to the conversion of energy of temperature and pressure to other forms of energy. The volume of gases under pressure within the chamber and bore behind the projectile base is shown by the line 109. It rises regularly as flight down the bore progresses. In the first analysis we assume that full rifling is provided in accordance with previous practice:

The projectile energy (total) is shown by the curve 110. This curve is plotted on the basis of assumption of full rifling, so that the full amount of spinning is due to rifling. The friction loss of energy due to friction of the projectile on the lands is computable, and is represented by the distance between the curve of projectile energy 110 and the next higher curve 111. The loss of energy by heating the barrel, etc., is represented by the distance between the curve 111 and the next higher curve 112. The loss of energy due to recoil of the barrel and parts is shown by the distance between the curve 112 and the next higher curve 113. The energy of velocity of the body of gases travelling along the barrel behind the projectile is shown by the distance between the curve 113 and the next higher curve 114. Consequently, the elevation of the curve 114 represents the combined energy of the above mentioned factors at any point along the barrel, and likewise the elevations of the other curves represent the combined amounts of energies of the several factors beneath them.

By deducting the elevation of the curve 114 from the elevation of the curve 107 we derive the curve 115 which represents the available energy of the combusted gases at any point along the barrel, not including the gas velocity energy; and by adding to the curve 115 the amount of gas velocity energy we get the curve 116, representing the available energy at any point along the barrel, including the gas velocity energy.

I have also plotted the curve 117 representing the elapsed time at any point along the barrel needed for the projectile to reach such point after commencement of flight, and the full line portion of this curve represents the condition for full rifling.

I have also plotted the curve 118 representing the factor "R" for the formula $PV=RT$, entering into certain of the computations herein made.

Now it is noted that the friction of the projectile bands on the lands of the rifling is very great, but heretofore necessary in order to produce full spinning of the projectile; so if we can discontinue such rifling at a point considerably short of the muzzle of the barrel we shall from that point forward correspondingly increase the acceleration of the projectile, since the gas pressure on the base of the projectile will be more fully applied to acceleration of the projectile. The so reduced spinning effect must then be made up by some other power, and I propose to do this by the supplemental use of the expanding gases in manner to be hereinafter set forth. I have therefore assumed that rifling may be discontinued at the location 119; and from that point forward to the muzzle I have plotted the supplemental or dotted line portions of the curves 110, 117 and 103, such dotted portions being indicated as 110^a, 117^a and 103^a, respectively. It is noted that thereby the muzzle velocity has been raised from 2600 ft./secs. to 2735 ft./secs. and that the muzzle energy has been increased from 703.7 ft./tons to 777.569 ft./tons, and the elapsed time has been reduced from 0.0092931 secs. to 0.0092536 secs. being the elapsed time from commencement of

flight until exit from muzzle. These are possible benefits or improvements in performance existing at the instant of exit from the muzzle, and without taking into account the energy to be added by improvements of my invention, other than the ability to reduce or eliminate the rifling friction.

At this point it may be noted that due to the very high gas pressure existing within the barrel just prior to the instant of projectile emergence, said gases are very dense, and have a correspondingly high specific gravity. For example, in the assumed case the total mass of these products of combustion, amounting to 4.874# is contained within a volume of 0.780 cu. ft. at the instant of muzzle opening, so that at that instant their weight per cubic foot is 6,249 pounds, giving a specific gravity of approximately one-tenth that of water. This weight per cubic foot and specific gravity fall very rapidly upon opening of the barrel due to projectile emergence, but nevertheless for a short interval we have the condition of emergence of a mass of matter from the muzzle at very high velocity and under a condition of relatively high specific gravity. It is desired to extract useful work therefrom.

In connection with the curves of Figure 12, the following additional comments should be here made;

Knowing the curve of gas pressure, 104, we are able to calculate from the area under this curve the total energy exerted on the base of the projectile during its flight down the barrel. This is found to be 920.65 ft./t. Deducting therefrom the total muzzle energy of the projectile (703.7 ft./t.) we get the difference of 216.95 ft./t. which is the loss due to friction during barrel flight. The form of the curve 111 may be similarly determined. Since the energy lost to the barrel by heat is assumed to be substantially equal to the friction loss to the barrel (see Ordnance and Gunnery, Tschappat, p. 145, ed. 1917) we may assume the heat loss to follow the line 112 of Figure 12, being separated from the line 111 by the same amount as the line 111 is separated from the line 110.

At the instant of emergence of the projectile, the recoil energy can be computed as based on the formula

$$v_f' = \frac{p + \frac{1}{2}c}{W} V$$

(see Tschappat, above, p. 316), and the distance between the curves 112 and 113 is based on this formula.

The energy of translation of the unburned charge and gases may be computed according to the formula

$$e = \frac{cv^2}{6g}$$

(see Tschappat above, p. 138), and the distance between the curves 113 and 114 is calculated accordingly.

The time elapsed curve 117 was readily calculated from the form of the velocity curve 103 of the projectile, knowing the distances along the barrel.

The temperature of combustion was estimated by the formula

$$t = \sqrt{\frac{4000bQ_{mv} + (a + 30b)^2 - a}{2b}}$$

(see Tschappat above, p. 74). This was assumed to be the temperature up to the time of comple-

tion of combustion. Thereafter the expansion was assumed to be adiabatic, and the temperature and pressure curves were related as shown in Figure 12.

According to one important feature of my present invention I propose to so form the base portion of the projectile that as the release of gases commences and continues (after commencement of the opening operation), the gases are forced to react against the base of the projectile, or against other portions of the projectile, in such manner that the direction of said gases during release is violently changed or reversed, thereby effecting a great increase of dynamic reaction of said releasing gases against the projectile base, and ensuring delivery of a great additional amount of energy to the projectile before said projectile passes so far away from the muzzle as to make further benefit impossible.

Sometimes I so arrange the parts that the interval during which this reaction condition may continue is greatly increased; and sometimes I so arrange the parts that one or more reactions against the side portions of the projectile as well as its base may be secured; and sometimes I employ various combinations of these several schemes.

In Figures 1 to 11, inclusive, I have shown several other arrangements embodying features of the present invention, and some of which are intended to make provision for still further increase of the time interval during which the expansion of the gases will take place under complete control. In the arrangement of Figures 1, 2, 3 and 4 I have shown an arrangement in which the features of my present invention are applied to a typical form of large caliber armour piercing shell, and substantially without change of the form of the shell proper. In this case the shell 166 is provided with the nose portion 167 of well understood form, and with the high explosive charge 168, together with the fuse 169 set into the base block 170. The usual sealing plate 171 is placed over the base block to prevent leakage of propellant gas into the interior of the shell.

In the present case I provide an extension on the base portion of the shell. Said extension includes the chambered member 172 which may be conveniently threaded to the base portion of the shell as shown at 173; and this chambered member is open at its rear end as shown at 174, having the wall 175 which establishes the chamber 176. The front end of this chamber is suitably formed to provide the forwardly and outwardly and then rearwardly curved surface 177, and a plurality of gas discharge openings 178 are provided in the wall 175 near the front end of the chamber 176 thereof. There is the central rearwardly extending nose portion which divides the chamber to establish the proper formation of the rear portions of the curved surfaces, so that forwardly flowing gases will be forced to flow over the backwardly curved portions of the surface 177 and can only reach the openings 178 after suffering a great reversal of direction of flow as they leave the device. Preferably a follower band 179 is placed on the rear end of the extension wall 175; and if desired a leader band 180 may be provided on the rear portion of the shell proper, and directly in advance of the threaded connection 173.

With the foregoing arrangement it will be seen that during normal flight down the barrel of the gun both of the bands will seal with the lands of the rifling, so that leakage is effectively pre-

vented. As soon as the leader band emerges from the muzzle the openings 178 become exposed and gas discharge from them commences. The follower band is still in sealing engagement with the rifling. The commencement of emergence of the openings 178 from the muzzle is shown in Figure 1. During flight from the instant of emergence or exposure of the openings 178 until the rear end of the extension wall 175 emerges from the muzzle, gas discharge through the openings 178 will continue, with the discharging gases suffering violent reversal of direction and generating a great forward reaction against the wall portions 177, in addition to the static pressure of said gases against said wall portions. The surfaces 177 (of Figures 1 and 2) may be so formed as to produce a rotary component of reaction of the exiting gases on the base portion of the projectile so as to cause the desired spinning of the projectile without the need of providing the usual rifling or as a supplement to the effect produced by such rifling; and likewise the surfaces of the base of the projectile shown in Figures 5, 6 and 7 may be so formed as to produce such rotary component of reaction, and this is also true of the form of projectile shown in Figures 8, 9, 10 and 11. Thus I have provided for recuperation of a large portion of the energy of the expanding gases and delivery of such energy into the projectile as additional muzzle energy in addition to that energy which would otherwise be delivered to the projectile. Furthermore, I have provided means to expand the gases from their high pressure within the barrel just prior to opening of the muzzle of the gun, with a relatively gradual expansion down to a much lower pressure prior to complete emergence of the projectile from the muzzle; and I have also provided arrangements such that during such expansion of the gases at release a large portion of the so released energy of the gases will be recuperated in the form of muzzle energy of the projectile.

The time interval during which such gas release and expansion will take place will depend on the distance between point of commencement of opening of the openings 178 and emergence of the end portion of the wall 175 from the muzzle, and the velocity of travel of the projectile during that interval. Since the velocity of the projectile during that interval is still being increased, the integrated time interval for such travel will determine the problem. Furthermore, the rate of gas discharge will depend on the cross-sectional area of the openings, the form of the passage, the gas pressure at commencement of discharge, the nature of the gases themselves, and other factors. The terminal or residual pressure existing within the barrel when the wall 175 finally emerges from the muzzle will also depend on the rate at which the gases have been escaping through the openings 178, the initial pressure when said openings first are exposed, the nature of the gases themselves, and various other factors. By proper design of the openings as respects size, contour, etc., the arrangement may be made such as to ensure a great reduction of pressure during the "expansion interval," and corresponding benefits in the form of energy added to the projectile may be secured.

As an illustration, in the case of a sixteen-inch shell emerging with a velocity of 2600 ft./sec. at the instant of commencement of exposure of the openings 178, and with the wall 175 of such

length as to require a travel of three feet during the interval of gas release, the time interval would be something less than .00115 sec. This is a very appreciable interval of time in which to effect gas discharge under the conditions here existing, and a very great lowering of gas pressure may be attained during this interval and under the controlled conditions herein explained. A great addition of muzzle energy may be made to the projectile under these conditions and during such time interval.

In order to close the openings 178 after emergence of the wall portion 175 from the muzzle, I have provided the sleeve 181 surrounding the said wall portion and slidably thereon. This sleeve may be advanced far enough over the extension to cover the openings, as will be apparent from Figure 4 wherein that condition has been attained. It will be noted that during acceleration of the projectile during its flight down the bore this sleeve will remain in its rearmost position on the wall 175 (as shown in Figure 1), leaving the openings 178 open as shown in that figure. After emergence of the projectile completely from the muzzle there will commence a very rapid deceleration of the projectile due to wind resistance, so that a force will be thereby created tending to cause said sleeve to move forwardly over the wall 175 to the closing position. Such deceleration may be as much as two or three times "G," so that a very considerable force will be generated tending to move the sleeve to the closing position of Figure 4. The closing of the openings 178 will prevent undesirable flow of air currents through these openings, and through the passage or chamber 176, such as would materially increase the resistance of the projectile during its free flight.

It is noted that the form of Figures 1, 2, 3 and 4 is one wherein the projectile is provided with a permanent addition to its length in order to secure the benefits of the added time interval during which the gases are being released under complete control. In the arrangement of Figures 5, 6 and 7 I have shown a scheme in which such extension portion is itself slidably mounted on the outside of the shell, so that during free flight said extension may advance over the shell and restore the overall dimensions of the projectile to substantially the size which they would have without such extension. In this case the sleeve 182 constituting the extension proper is slidably mounted on the projectile, being preferably splined thereon as shown especially in Figure 7. The front end of this sleeve is provided with a shouldered portion 183 which will engage the properly shouldered portion of the rear end of the projectile when the extension is in its rearmost position (that of Figure 5) during acceleration in the barrel. On the contrary, after free flight commences the deceleration of the projectile in the air will cause said extension sleeve portion to move forwardly over the exterior of the projectile into the position shown in Figure 6.

The base portion of the projectile proper is formed as shown so that the desired curvature of surfaces is produced for recuperation of energy from the exiting gases either with or without production of a rotary component of reaction on the projectile. The sleeve portion 182 is provided with the ports or openings 184 which will occupy the proper positions with respect to the said curved surface when the extension is in its rearmost position. With this arrangement it

is also desirable to provide the leader band 185 on the front end of the extension sleeve, and the follower band 186 on its rear end portion. Due to the splining of the sleeve on the body of the projectile the proper rotary driving connections will be established to the body of the projectile at all times, together with the proper gas sealing actions.

Examination of Figure 6 in particular will show that with this arrangement we are able to secure the greatly prolonged interval of time for gas discharge under complete control, and with the benefit of substantially no increase in the length of the projectile during the time of free flight. Furthermore, the central rearwardly extending portion of the base of the projectile, 187, serves to give to the projectile a "boat-tailing" form during free flight, with the attendant advantages.

In Figures 8, 9, 10 and 11 I have shown a further embodiment of my invention wherein the features of the two forms just described are more or less combined into a "hybrid" form. Furthermore this arrangement of Figures 8 to 11 is one wherein a still greater time interval of controlled gas discharge is secured. In the present case I provide on the base portion of the projectile the permanent extension or wall 188, forming the chamber 189 of form similar to the chamber 176, and with the forward end of said chamber 189 having the curved surfaces 190 according to the previously explained arrangements. The openings 191 are also provided for gas discharge. Then I provide the slideable sleeve 192 which may slide over both the extension wall 188 and over the body of the projectile proper, the forward end of this sleeve being provided with the shouldered portion 193, and the rear end of the permanent extension wall 188 being provided with a corresponding shouldered portion 194 to prevent complete backward freeing of the sleeve from the permanent extension. Both the sleeve portion 192 and the outside faces of the permanent extension 188 and of the projectile proper are splined so that rotary driving connections are established between the sleeve 192 and said parts. Furthermore, the projectile proper may be provided with the leader band 195, and the rear end portion of the sleeve 192 may be provided with the follower band 196 as shown.

With this arrangement it will be seen that a very great increase of the time interval during which gas discharge under control will occur is secured, together with an increase of the permanent length of the projectile equal only to the length of the extension portion 188. The sleeve portion 192 will slide forwardly to its extreme forward position after free flight begins, due to the aforementioned deceleration, and will thereby reduce the overall length of the projectile during free flight; and at the same time the forward movement of the sleeve 192 will result in closing of the openings 191 during free flight.

It is now apparent that I have herein illustrated and described embodiments of my invention wherein features thereof are usable in either light or heavy ordnance in which the gas pressures are very high, both during normal flight down the barrel as well as at the muzzle opening (the temperatures being correspondingly high); and they may be incorporated in other forms of ordnance in which relatively low pressures and projectile velocities are used, such as

mortars for throwing trench grenades and the like.

Now it is to be noted that the end products from the combustion of the propellant are complex, and include various gases, which have hereinbefore been referred to. These generally include CO_2 , CO , H_2O , H_2 , and N_2 . Of these the hydrogen and nitrogen are perfect or permanent or fixed gases, and they will follow the laws of such fixed gases closely during expansion of an adiabatic nature. Such expansion it is to be remembered takes place during the interval when the gas release openings are open, as well as during flight down the barrel after combustion is complete. Probably the CO_2 will also follow these laws rather closely; but the H_2O will probably be in a condition or partial dis-association due to the high temperatures existing within the barrel, and the condition of the CO in the presence of the CO_2 and H_2O within the barrel is uncertain. The H_2 and CO released by the reactions, will burn in the air after release from the muzzle, but this energy of combustion is not included in the estimate of available energy of combustion of the propellant.

If it be assumed that a greater recovery of energy by reaction according to the principles herein disclosed be possible in the case of release of permanent or fixed gases than in the case of such gases as CO_2 , CO , and H_2O , then it will be found possible to effect greater recoveries according to my invention when using propellants whose end products are higher in H_2 and N_2 , and lower in CO_2 , CO , and H_2O , than vice versa. Accordingly, the following comments are in order:

Deca-nitrocellulose propellant contains substantially 12.75% N. This propellant

gives end products as follows;

with volumes of 14, 10, 2, 13 and 5, respectively; total heat of 1,474,000 ft. lbs.

Ennea-nitrocellulose propellant contains substantially 11.966% N. This propellant

gives end products as follows;

with volumes of 10, 14, 4, 11.5, and 4.5, respectively; total heat of 1,293,400 ft. lbs.

Octa-nitrocellulose propellant contains substantially 11.111% N. This propellant

gives end products as follows;

with volumes of 6, 18, 6, 10 and 4, respectively; total heat of 1,095,200 ft. lbs.

The above total heats do not include heat of combustion of H_2 and CO after leaving the gun.

Now the proportion of the fixed or perfect gases contained in the foregoing end products is much greater in the case of deca than in the case of either of the other propellants. Consequently it would be expected that a better recovery of energy should be possible when using the deca propellant, or other propellants giving large percentages of fixed or perfect gases, than when using propellants giving lesser percentages of fixed or perfect gases in their end products. Still I do not intend to limit the use of the features of

my present invention to the deca propellant, or any other specific propellant, except as I may do so in the claims to follow. The foregoing examples of certain propellants are given merely by way of illustration, and not by way of any limitation of my invention or its features.

With respect to such embodiments of features of my invention as those shown in Figures 5 to 7, inclusive, or 8 to 11, inclusive, it is to be noted that in loading such projectiles as therein illustrated into the gun the sliding extension portions or sleeves (182 or 192) should preferably stand in their forward or telescoped positions when loaded, and prior to commencement of flight down the barrel, as thereby the interference with the charge in the chamber will be reduced to a minimum. For example, with the arrangement, shown in Figures 5, 6 and 7, the length of the projectile when the extension 182 is thus telescoped is substantially the same as it would be without such extension member. Such a projectile may therefore be loaded into the gun in the same manner as previously known forms of projectiles not embodying the present invention features. Such being the case it is evident that during flight down the barrel this extension member or sleeve must trail back of the main body of the projectile so that when the muzzle is reached the extension will be in its extended position, such as illustrated in Figure 5 (or in Figure 8, as the case may be). Such trailing action will occur as I shall now explain:

Considering the form of Figures 5, 6 and 7, when the extension or sleeve 182 is set forwardly over the body of the projectile (into the position of Figure 6), if it be assumed that there is no gas leakage between the sleeve and the body of the projectile, so that no gas can reach the front end of the extension sleeve to exert back pressure thereon, we shall have the condition that the acceleration force exerted on the sleeve will be proportionate to its annular area at its back end, and which is exposed to the gas pressure; and shall have the further condition that the mass to be accelerated by this force will be substantially the mass of a solid body of steel or the like extending the length of such sleeve. The rate of acceleration will be the force divided by the mass as above. Likewise, the acceleration of the main body of the projectile will be equal to the propellant force exerted on its exposed base area (which is reduced in amount equal to the area of the rear end of the sleeve), divided by the mass of the body of the projectile proper. It is noted that the projectile proper, in the case of a loaded shell, is much lighter, per cubic inch or cubic foot, than a solid body of steel or the like, so that the rate of acceleration of the body portion of the projectile will be greater than that of the telescoping sleeve element. Consequently, even under the adverse condition that no gas pressure may reach the front end of the sleeve it is evident that the main body portion of the projectile will accelerate faster than the sleeve portion, so that by the time the projectile reaches the muzzle the sleeve will have been set backward its extreme distance and into its working position. This fact is further assured by reason of the fact that the friction of the follower band 186 or 196 on the lands is large so that the major portion, if not all, the friction to be overcome during acceleration is on the sleeve element, leaving the main body portion of the projectile free to accelerate under the pressure being exerted on its base.

If there should be leakage of gas past the sleeve so that pressure should be exerted in advance of it, we should have a still more favorable condition for ensuring the desired trailing action to which we have just referred. In some cases it may be desirable to ensure gas pressure against the front end of the sleeve so as to ensure that said sleeve will not be accelerated as fast as the body of the projectile, and to ensure that the sleeve will be extended back into its working position when the muzzle is reached. For this purpose passages such as 238 of Figure 6 may be provided in the base portion of the projectile, same being of small size and merely for balance of gas pressure during flight down the barrel of the gun.

Manifestly, when a leader band is used in advance of the gas openings, such band will seal against leakage of gas through the openings until the band leaves the muzzle, as which time gas discharge through the openings is intended to occur.

In the case of armour piercing shells and the like, it may be noted that when using a telescoping sleeve arrangement said sleeve is contained with the diameter of the shell as determined by the bourrelet. Consequently the action of the shell provided with features of my present invention is not materially changed. Furthermore it is to be noted that such a telescoping sleeve is splined to the body of the shell by spline connections at the front end of the sleeve, so that when said sleeve is advanced over the body of the shell such splined connection is close to the nose of the shell body. Now the radius of gyration of such a sleeve is large, since the entire mass of such sleeve is located at almost the full diameter of the shell. Consequently the rotary energy of the sleeve constitutes a substantial proportion of the total rotary energy of the projectile in free flight. Due to the fact that the splined connection between the sleeve and the body portion is close to the nose, such rotary energy of the sleeve is transmitted directly to the nose portion at the instant of impact, and as a result the tendency of the projectile to twist off when the nose welds to the armour plate or other obstruction is much reduced.

Due to the large radius of gyration of such an extension as the chambered portion 175 of Figure 1, or 188-192 of Figure 9, it is evident that such extension in itself will have a large amount of rotary energy in addition to that of the body portion of the projectile. Due to this fact it is not necessary to provide for as high a rate of rotation with such forms of projectile as in the case of projectiles not provided with such extension portion, and therefore the rifling when used may be further reduced, with consequent reductions of cost of gun manufacture, and upkeep, as well as reduction of friction loss on the lands.

It is noted that such permanent extensions as shown in Figure 1 and elsewhere herein may be readily attached to existing constructions of projectiles with relatively small cost, and with the advantages attendant on the use thereof. It is further noted that when loading a projectile having such a permanent extension, a portion, at least, of such extension may be allowed to reach back into the chamber. In such case a portion, at least, of the propellant charge may be loaded directly into the chamber of such permanent extension, and thus without interference with present designs of guns and projectiles. Any change in the density of loading entailed by such scheme

of loading may be readily compensated for in the loading calculations.

It is noted that during the gas release interval, the wall of the sleeve or of the extension is subjected to a bursting strain due to the gas pressure still existing within the barrel and such sleeve or extension. That pressure will commence at substantially the amount of the "muzzle pressure" which would exist at the instant of release had the features of my present invention not been used (in the case shown by the curves hereof, amounting to 13,750 lbs./sq. in.). That pressure will then fall rapidly to its final value at the instant of complete emergence of the projectile. It is possible to work such sleeve or extension up close to the elastic limit of the metal thereof, so the wall thereof may be made relatively thin in comparison with gun designs themselves.

It is pointed out that the delivery of energy from the gas to the projectile in various forms herein shown is due to both the reaction of the gas against the base portion of the projectile, due to its velocity and change of direction, and also, in some embodiments herein illustrated, to the static reaction of the high pressure gas against the base of the projectile. This latter portion of energy saving may or may not be included in the estimated increase of muzzle energy of the projectile, depending on the purpose of the estimate. Still it is to be noted that the reaction saving due to dynamic reaction of the velocity gas against the curved surface is much larger than such static pressure saving of energy during the interval of gas release through the discharge openings.

In an estimated case of a three inch gun incorporating features of my present invention the possible increase of projectile velocity is from 2600 ft./sec. to substantially 4000 ft./sec., with increase of muzzle energy from 703.7 ft. tons to substantially 1600 ft. tons; involving more than doubling the projectile's energy, and with corresponding increase of velocity at the instant of commencement of free flight. Such estimated increases are accomplished without reduction of rotary or spinning rate.

Of the foregoing estimated increase of projectile energy only a small portion is due to static pressure of the gases against the projectile base.

Now it is to be noted that increase of muzzle energy and efficiency by increase of gun length or number of calibers, so as to provide for increased expansion of the gases, is a totally different matter from the schemes herein disclosed, since it does not make any provision for extraction of energy from the gases by means of the dynamic reaction principle. In any case, whatever may be the gun length, the further use of features of my present invention will afford further increase of projectile energy and gain of efficiency.

It is to be noted that, for any selected set of conditions the sizes of the gas delivery ports, and the time interval during which controlled gas escape will occur, may be so determined that gas pressure reduction during this interval will be to some approximate final or terminal value, with corresponding improvements in performance. Manifestly, by increase of size of port openings the rate of gas discharge will be increased, with corresponding reduction of the time interval to secure a pre-selected drop of gas pressure prior to final complete emergence of the projectile from the muzzle, but too great size of these port openings is undesirable as it will result in partial loss

of control of gas reaction during the gas discharge interval. On the contrary, too small ports will prevent sufficiently rapid drop of gas pressure to secure a desired small end pressure without too great length of the sleeves or extension on the rear end of the projectile, or corresponding scheme. It is therefore evident that in any case the various factors herein especially referred to should be properly related to ensure best or pre-selected results of operation. This can be done. I do not intend to limit myself to any specified proportions or sizes of these or other parts, except as I may do so in the claims to follow.

In Figure 13 I have shown in fragmentary longitudinal section the base portion of still another detailed form of projectile embodying the features of my present invention. In this case the base portion 238^a of the projectile has its rear face 239 so formed as to ensure gas discharge backwardly at an angle of substantially thirty degrees to the direction of flight which direction is indicated by the arrow. Furthermore, the base portion is so formed that definite rearwardly extending passages are provided through which the gases are discharged, said passages extending from the central or axial portion 240 to the discharge openings 241; and these passages are so formed that they include delivery portions prior to reaching the openings which delivery portions reach backwardly for an appreciable distance in such direction of substantially thirty degrees to the direction of flight, thereby ensuring a directed discharge in a definite direction with respect to the direction of flight. Consequently I am able to ensure controlled delivery of the gases prior to their expansion into the atmosphere, and with recovery of energy according to features of the present invention.

Now it is evident that the full recovery of energy which might be recovered (as hereinbefore analyzed) would be possible only in the assumed case that the gases were so delivered that they had no velocity after discharge. Such condition is not practically feasible, but may be approached. If the gases were to be delivered from the passages of the projectile with such projectile stationary said gases would have a backward velocity; but it is evident that they must also have a lateral or sidewise velocity so that they may clear the projectile and the gun itself. In other words, the passages should be so designed that they will deliver the gases outwardly as well as rearwardly. In the case shown in Figure 13 they are delivered through passages extending outwardly at an angle of thirty degrees with respect to the direction of flight, but any other suitable design might be substituted.

Now the forward velocity of the projectile at the instant of discharge of any small quantity of the gases being discharged must also be considered in determining the actual direction and velocity of gas delivery; and if the projectile velocity should be one half the gas delivery velocity (in the direction of flight) it would theoretically be possible to cause gas delivery without any velocity in the direction of flight, but nevertheless with some lateral velocity due to the non-flight (or contra-non-flight) direction of gas delivery.

In Figure 13 I have shown by vector lines and more or less diagrammatically the relations between the several velocities just above referred to, and for three conditions of velocities. Thus, line 242 represents by its length and direction the velocity and direction of discharge of gases for the condition of stationary projectile, and under one

set of conditions; and the line 243 represents the corresponding velocity of projectile in its direction of flight. Then the line 244 represents the resultant of these two velocities, and therefore the actual velocity and direction of gas delivery under the assumed conditions of projectile velocity, gas delivery velocity, and direction of passages in the base portion of the projectile. Likewise, for a condition of greater projectile velocity and smaller gas discharge velocity the lines 245 and 250 represent the gas discharge velocity and the projectile velocity, and the line 247 represents the resulting actual velocity and direction of gas discharge; and for another condition of still greater projectile velocity and still smaller gas discharge velocity, the lines 246 and 251 represent the gas discharge velocity and the projectile velocity, and the line 248 represents the resulting actual velocity and direction of gas discharge.

It will be noted that if V_g represents the gas discharge velocity (with stationary projectile), and V_p represents the projectile velocity, and V_1 represents the lateral component of gas velocity, then $V_1 = V_g \sin A$; where A is the angle of gas discharge (stationary projectile) with respect to the direction of flight. Likewise, the component of gas velocity in the direction of flight (stationary projectile), which may be called $V_f = V_g \cos A$. Again, taking into account the projectile velocity we find that the remaining velocity of the gases in the direction of flight, which may be called $V_r = V_f - V_p$, or (substituting), $V_r = V_g \cos A - V_p$. This means, of course, that when the component of gas velocity backwardly equals the projectile velocity, the gases will be delivered directly outwardly, and with a velocity laterally dependent on the angle of the gas delivery portions of the passages in the base of the projectile. It is desirable to keep that angle as small as possible in order that this lateral component may be as small as possible, and with consequent reduction of final wastage of energy in the gases due to velocity, since that energy depends on the square of said velocity.

It is also evident from the above analysis that in case of a projectile velocity greater than the backward component of gas delivery velocity the gases will have a forward component of velocity at delivery.

Now the determination of the actual possible recovery of energy from the discharging or exiting gases is a complex determination, and it involves consideration of many factors, some of which include constants of uncertain value and kind. Still it is possible to make an approximation of the amount of such recovery; and for this purpose I have made use of what I may call the "Quantum" method. By this method the total distance of travel of the projectile from the instant of commencement of opening of the discharge openings to the instant of complete exit of the tail end of the projectile from contact with the muzzle (in other words, the total travel of the projectile while gases are being delivered under control), is subdivided into numerous small distances or differentials of travel, and the conditions of gas pressure, temperature, velocity of discharge, etc., are analyzed and determined for each of these zones or positions, or stages. The procedure is then as follows:

1. Projectile velocity and gas velocity at commencement of stage are assumed to be equal.
2. Estimated velocity of emergence of gas from orifices during travel through stage was based on estimated total energy remaining in gas (ig-

noring gas velocity energy, see curves), and on total mass of gas remaining in barrel, and this estimated velocity was taken as the velocity of emergence of the small quantum of gas which would emerge during the travel through the stage in question. The energy necessary to press back the atmosphere was also deducted in estimating the available energy to create gas velocity, as well as the energy remaining in the expanded gases in the form of heat, above zero Cent.

3. The time consumed in travelling through the stage was estimated on the basis of projectile velocity at the beginning of the stage.

4. The length of travel of the emerging gases during this interval of time was found.

5. The volume of gas discharged during this interval of time was estimated on the basis of the length of the stream of gas discharged as above calculated.

6. The original volume of gas was taken as the volume at the beginning of the stage.

7. The equivalent volume of gas in its expanded condition at the end of the stage was calculated as the original volume at the beginning of the stage plus the volume discharged.

8. The pressure of the gas remaining in the barrel at the end of the stage was calculated from the equivalent volume at the end of the stage by the formula $PV = P'V'$.

9. The average pressure existing in the barrel during the stage travel was calculated as the mean between the pressures at the beginning and ending of the stage travel.

10. The work performed on the base of the projectile during travel through the stage was estimated from this average pressure (being work due to actual pressure on the base of the projectile).

11. The friction loss during travel through the stage was estimated from the length of travel and assuming a total friction of 2500# (for three inch projectile), there being no rifling.

12. Work performed on the base of projectile (10) minus friction loss (11) equals pressure energy available to increase total energy of projectile.

13. The temperature of the gas at the end of the stage was found from the formula $PV = RT$, and on the assumption that R varies regularly from the value of 3.792 at the muzzle to the value of 3.7406 for full expansion.

14. The heat loss to the barrel and parts during the travel along the stage in question was estimated as follows: It was assumed that the heat loss constant depends on time of exposure to the hot gases as well as temperature of the gases (being so much higher at all times than the temperature of the barrel). The heat loss (integrated) for the muzzle position equals 163 F. T. (see curves). Time consumed to reach muzzle equals .0039231 sec. (see curves). Average temperature of gas during flight down the barrel equals 2860 degrees Cent. (above zero) (see curves). Then, energy loss per sec. per degree Cent. equals

$$K = \frac{163}{.0039231 \times 2860} = 14.527 \text{ F. T.}$$

Having the foregoing constant, it is possible to estimate the heat loss to the barrel during each stage examined, assuming the velocity equals that at the beginning of the stage, the temperature having been found from 13.

15. Deducting energy performed on base of projectile (10) and heat loss to the barrel (14) from

energy at beginning of stage we get energy available to give velocity to the expanding gases or energy remaining in the gas at end of stage. This will be total energy in the body of gas remaining within the orifices, and undischarged.

16. The amount (volume) of gas discharged during the stage was found by first deducting the actual volume within the barrel (including the volume within the stage or stages so far considered) from the equivalent volume (see 7). This discharged volume of gas is at a certain pressure and temperature, but the ratio of volume within the barrel (plus stages) compared to equivalent volume is then applied to the mass of gas in the barrel (and stages) at the beginning of the stage being examined, thereby ascertaining actual amount of gas discharged during the stage.

17. To ascertain the energy carried out of the barrel (and stages) by the discharged gas we apply the ratio of (16). This ratio applied to the energy remaining in the gas at end of stage (15) gives energy remaining in gas still enclosed; and energy remaining in gas still enclosed deducted from total remaining energy at end of stage (15) gives energy to create velocity in discharged gas (found in 16). Thereby we are able to compute velocity of discharge of gas during the stage in question.

18. Gas discharged flows in some direction determined by velocity of discharging gas (absolute) compared to velocity of projectile during the stage in question, and taking account of angle of discharge (assumed as thirty degrees). For this purpose use was made of a vector diagram for each stage. On this diagram the velocity of gas discharge was plotted backwardly and outwardly at thirty degrees from the direction of flight; then directly forward (at velocity equal to projectile velocity); and the resultant gave the actual velocity and direction of gas delivery.

By the use of such an analysis, applied to each of numerous stages it was possible to estimate the probable recovery of energy in the given case of a three inch gun; and it was found that it should be possible thereby to recover energy sufficient to double or more the projectile energy at the muzzle of the gun, compared to previous practice, not making use of features of my present invention.

Where in the claims to follow I speak of a "shot section" of the projectile I contemplate not only projectiles having solid "shot" bodies but also projectiles having loaded or explosive or "shell" sections.

I claim:

1. A projectile for ordnance comprising a shot section having its base portion provided with a forwardly and outwardly and rearwardly curved surface facing towards the gases released from the gun with which said projectile is intended

to be used, whereby the gases as released from the muzzle of the gun during flight of the projectile from said muzzle impinge against such surfaces of the projectile base and are deflected

5 rearwardly with consequent increase of muzzle energy of the projectile, together with a rearwardly extending skirt telescopingly mounted on the projectile of size to cooperate with the bore of the gun and maintain substantially gas tight engagement with the gun bore after passage of the aforesaid curved surface past the muzzle of the gun and until departure of said skirt from the muzzle of the gun, said skirt having a series 10 of gas discharge orifices therethrough substantially in the zone of the periphery of said rearwardly curved surface aforesaid, for discharge of gases during the interval between passage of the peripheral portion of said curved surface beyond the muzzle of the gun and the time of flight 15 of said skirt portion from the gun muzzle, substantially as described.

2. In a projectile as defined in claim 1, that improvement comprising the telescoping of said skirt externally of the shot section, for telescopic 20 movement forwardly over the shot section during deceleration of the projectile after commencement of free flight, to thereby reduce the axial dimension of the projectile after exit from the gun, substantially as described.

3. In a projectile as defined in claim 1, that improvement comprising provision of a band on the rear portion of said skirt for sealing engagement with the bore of the gun after passage of said gas discharge openings beyond the muzzle of 35 the gun, substantially as described.

4. In a projectile as defined in claim 1, wherein in said forwardly and outwardly and rearwardly curved surface is also curved angularly with respect to the axis of the projectile, whereby 40 the gases are discharged through said openings with a component of movement in a rotary direction about the axis of the projectile, to thereby create a rotative force on the projectile to spin said projectile, substantially as described.

45 THOS. A. BANNING, JR.
